UNITED STATES PATENT OFFICE

ARTHUR B. MODINE, OF RACINE, WISCONSIN, ASSIGNOR TO MODINE MANUFACTURING COMPANY, OF RACINE, WISCONSIN, A CORPORATION OF WISCONSIN

RADIATOR

Application filed November 22, 1929. Serial No. 409,017.

The invention relates to heat exchange devices such as are used for the purpose of heating apartments, dwellings, etc., and has as its principal object the provision of a construction whereby air may be heated by radiation, conduction and convection.

The invention has as an object the provision of a device of this character having means through which the heating medium is circulated having an element extending therefrom which is heated by conduction by said means, said means and said element being arranged relatively to each other so that air contacting therewith will be heated and by means of convection, be circulated into the room to be heated. A further object of the invention is to construct the device so as to provide a radiator, having an element which is heated by conduction, said radiator and element providing a plurality of vertically arranged flues producing air passages which act to conduct and heat air during circulation through said passages.

Another object of the invention is to provide a structure such as that above referred to with heat radiating fins and to arrange said structure in a casing, in a manner so that cool air may be introduced into the casing at the lower end thereof and be discharged from the casing at another point, preferably near the upper portion of the casing.

It is an object to construct the radiator portion of the device through which the heating medium circulates so that a plurality of extensions and recesses are provided between which air may circulate, become heated and be discharged therefrom into the casing and thence into the room to be heated.

The invention has these and other objects, all of which will be clearly understood when read in conjunction with the accompanying drawing which discloses two arrangements which may be resorted to, it being obvious that changes and modifications may be resorted to without departing from the spirit of the appended claims forming a part hereof.

In the drawing:

Fig. 1 is a front view partially broken away for the purpose of illustration;

Fig. 2 is an enlarged section taken on line 2-2 of Fig. 1;

Fig. 3 is a sectional view similar to Fig. 2 showing a modified arrangement;

Fig. 4 is a horizontal section taken on line 4-4 of Fig. 3; and

Fig. 5 is a perspective view of a portion of the structure shown in Fig. 3.

The structure disclosed in the drawing for accomplishing the advantages above enumerated contemplates the utilization of a radiator section generally designated 10 having the fluid inlet and outlet pipes respectively designated 11 and 12 connected therewith. One wall of the radiator or heat exchange device generally designated 10 is provided with an element 13 which extends a suitable distance beyond the upper edge of the heat exchange device and has its upper end preferably connected with a wall 14 of a casing generally designated 15. The side walls 16 and 17 of the casing are connected with the heat exchange device 10 and the extension 13 thereof, by any suitable means and therefore may be welded or bolted together. The heat exchange device 10 including the extension 13 is arranged relatively to the lowermost end of the casing to provide an opening 18.

In one embodiment of the invention, the heat exchange device 10 is arranged in spaced relation to the rear wall 15 of the casing and thus as relatively cool air enters the opening 18, said air will contact with the heat exchange device 10, become heated and by convection be transmitted through the casing and out through the openings 19 provided in the upper end of the extension 13. The front wall of the heat exchange device generally designated 10 of which the element 13 is a part is provided with a plurality of recesses and extensions respectively designated 20 and 21 and the rear wall such as 22 of the heat exchange device is similarly formed, it being understood that the edges of the rear wall 22 and the front wall of the heat exchange device are connected together in a manner to provide the end walls of the radiator 10 and may be connected together in any suitable manner, as for instance, by the lock seams 23 and 24. The open ends of the structure thus formed

are closed by caps or closures respectively designated 25 and 26, the caps being formed to correspond in outline with the interior of the heat exchange device 10, the caps being 6 welded or otherwise secured in place to provide a chamber or radiator through which the heating medium may circulate to transmit heat to the extension 13 forming the front wall thereof and also heat that air passing 10 through the opening 18 into and out of the casting within which the device is located.

It is one of the objects of the invention to provide a construction of this character which will allow relatively thin and cheap material to be employed in the formation of the structure and provision is made to add strength and life to the device by the resistance to rust and corrosion. To this end, the heat exchange device or radiator section 10 15 is provided with an inner lining 27 which conforms to the outline of the tank or radiator section 10.

It is evident from the foregoing explanation of the relative arrangement of radiator section 10 and the extension 13 that this arrangement of these parts forms a recess generally designated 28 which is located above the radiator and thus a portion of the air entering the opening 18 will contact with the inner face of the extension 13, and thus retain the heat transmitted to it by virtue of its contact with the wall 22 of the radiator 10, and reduce its heat loss as it is evident that the heated extension 13 will assist in heating the air somewhat, prior to discharge of the heated air through the openings 19 of the casing. It is contemplated to employ a humidifier 29 and to arrange the humidifier in the upper portion of the casing in a manner to allow heated air to pass between the humidifier and the wall 15 of the casing and thence over the open end of the humidifier and out into the room. The humidifier may, if so desired, be provided with the curved wall 30 which will act to deflect the heated air toward the openings 19 provided in the extension 13.

Another embodiment of the invention contemplates the utilization of heat radiating fins 31 which may be of any one of many constructions, that herein shown being comprised of a band of metal which is corrugated to provide a plurality of tubular passages and recesses respectively designated 32—33, between which the relatively cool air passes and is partially heated thereby prior to its engagement with the rear wall 22 of the radiator 10.

From the foregoing description of the structure, it is manifest that a heat exchange 60 device is provided whereby air is heated by radiation and conduction and caused to be discharged from the interior of the casing by convection. It is further evident that by forming the radiator and the extension 13 thereof to provide a plurality of vertically

arranged recesses and extensions that these, in effect, produce a plurality of flues which guide the heated air in a manner to result in increasing the heating efficiency of the device and in addition increases the heat radiating 70 surfaces of devices of this character. It is also evident that by forming the rear wall of the radiator section 10 in a like manner that the same advantage results at this portion of the structure. In addition to the above, it 75 is evident that by arranging the extension 13 and the radiator section 10 in the manner disclosed, that a recess is formed above the radiator into which the heated air is discharged from the radiator, which will maintain the 80 air at a degree substantially corresponding to that of the air as it leaves the radiator 10, it being manifest that a certain degree of heat is also radiated from the upper end of the radiator section 10 which is also transmitted 85 to the heated air contained in the recess.

Having thus described the invention, what I claim and desire to cover by Letters Patent is:

1. In a heat exchange device, the combination of a member having a fluid inlet and a fluid outlet, a wall thereof being extended beyond said member and said member and wall being arranged relatively to each other to provide means for heating air by convection said member being offset relatively to said wall in the direction of the path of air to be heated by convection and having a plurality of air passages.

2. In a heat exchange device, the combination of a chambered member having a fluid inlet and a fluid outlet, an element extending upwardly from said chambered member providing means for heating air by conduction, said chambered member having a wall thereof provided with a plurality of air passages, said member and element being arranged relatively to each other to provide means for heating air by radiation, conduction and convection.

3. In a heat exchange device, the combination of a chambered member having a fluid inlet and a fluid outlet, a wall thereof having a plurality of vertical extensions and recesses, said wall being extended beyond said chamber, and said chamber being arranged with respect to said wall to provide a recess at one side of said wall, said chamber, wall and recess providing means for heating air by radiation, conduction and convection.

4. In a heat exchange device, the combination of a chambered member having a fluid inlet and a fluid outlet, an element extending from said chambered member and being arranged relatively to said chambered member to provide a wall of a recess located above and lengthwise of said chambered member, said wall and member having a plurality of vertical air passages.

5. In a heat exchange device, the combination of a chambered member having a fluid inlet and a fluid outlet, an element extending from said chambered member and being arranged relatively to said chambered member to provide a wall of a recess located above said chambered member, said element and wall of said chamber having a plurality of vertically arranged extensions and recesses, the recesses provided in one wall of said chamber providing air passages leading to said recess located above the chambered member.

6. In a heat exchange device, the combination of a chambered member having a fluid inlet and a fluid outlet, an element extending from said chambered member and being arranged relatively to said chambered member to provide a wall of a recess located above said chambered member, said element and walls of said chamber having a plurality of vertically arranged extensions and recesses, the recesses provided in one wall of said chamber providing air passages leading to said recess located above the chambered member, and heat radiating fins connected with said chambered member.

7. In a heat exchange device, the combination of a chambered member having an inlet for heating media and an outlet therefor, said chambered member having an element extending beyond one edge thereof, the chamber being offset relatively to said element to provide a recess above the chambered member, and a casing having an opening near its upper end communicating with said recess.

8. In a heat exchange device, the combination of a chambered member having a fluid inlet and a fluid outlet, said member having an element extending beyond one edge thereof, the chamber being offset relatively to said element to provide a recess above the chambered member, a casing, said element providing a wall of said casing and having an opening near its upper end communicating with said recess.

9. In a heat exchange device, the combination of a chambered member having a fluid inlet and a fluid outlet, said member having an element extending beyond one edge thereof, the chamber being offset relatively to said element to provide a recess above the chambered member, a casing, said element providing a wall of said casing and having an opening near its upper end communicating with said recess, said chambered member being located adjacent and in spaced relation to an end and a wall of said casing.

10. A heat exchange device comprised of a member consisting of a pair of elements, one of which provides a radiator and the other an element adapted to be heated by conduction, said elements respectively extending inwardly from opposite edges of said member and terminating in a connection with

each other, and said element providing said radiator having openings respectively adapted to be connected with a fluid supply and a fluid return of a heating system.

11. A heat exchange device comprised of a member consisting of a pair of elements, one of which provides a radiator and the other an element adapted to be heated by conduction, said elements respectively extending inwardly from opposite edges of said member and terminating in a connection with each other, said element providing said radiator having openings respectively adapted to be connected with a fluid supply and a fluid return of a heating system, and heat radiating fins provided upon said element providing said radiator.

12. A heat exchange device comprised of a member consisting of a pair of elements, one of which provides a radiator and the other an element adapted to be heated by conduction, said elements respectively extending inwardly from opposite edges of said member and terminating in a connection with each other, said element providing said radiator having openings respectively adapted to be connected with a fluid supply and a fluid return of a heating system, and means providing tubular air passages connected with said radiator.

13. A heat exchange device comprised of a member consisting of a pair of elements, one of which provides a radiator and the other an element to be heated by conduction, said element providing said radiator extending from one edge of said member toward the opposite end of said member and having the opposite ends thereof arranged adjacent opposite side edges of said second mentioned element and said second mentioned element having openings provided therein adjacent an edge of said member opposite said edge from which said radiator extends, said radiator having a fluid inlet and a fluid outlet adapted to be respectively connected with a fluid supply and return pipe.

14. A heat exchange device comprised of a member consisting of a pair of elements respectively providing a radiator and an element to be heated by conduction, said element providing the radiator being located at one end of said member and extending therefrom toward the opposite end of said member and terminating in spaced relation to said end to thus provide said element to be heated by conduction, and said element providing said radiator having openings respectively providing a fluid inlet and a fluid outlet for said radiator.

15. A heat exchange device comprised of a member consisting of a pair of elements respectively providing a radiator and an element to be heated by conduction, said element providing the radiator being located at one end of said member and extending

therefrom toward the opposite end of said member and terminating in spaced relation to said end to thus provide said element to be heated by conduction, said last mentioned element and said element providing said radiator providing portions, one of which extends beyond the other to provide a recess above said radiator.

16. A heat exchange device comprised of a member consisting of a pair of elements respectively providing a radiator and an element to be heated by conduction, said element providing the radiator being located at one end of said member and extending therefrom toward the opposite end of said member and terminating in spaced relation to said end to thus provide said element to be heated by conduction, and said element providing said radiator having openings respectively providing a fluid inlet and a fluid outlet for said radiator, said element providing said radiator having a wall thereof provided with a plurality of passages leading to said recess.

17. In witness whereof, I hereunto subscribe my name this 6th day of November, A. D. 1929.

ARTHUR B. MODINE.
